To all whom it may concern:

Be it known that I, Kibbey W. Figure 2 is a front view of the machine, with the wings and footboards in open position, per-

mitting access to certain of the apparatus carried by the machine.

Figure 3 is a view similar to Figure 2, but from the rear of the machine.

Figure 4 is a side view of the machine showing the derrick extended ready for use.

Figure 5 is a view similar to Figure 4, but from the opposite side of the machine, with the derrick retracted and the aeroplane testing mechanism extended into position for operation.

I claim:

The ornamental design for a portable machine shop as shown and described.
